UNITED STATES PATENT OFFICE.

CHARLES A. SKENE, OF WESTMORELAND, KANSAS.

IMPRESSION-SHEET FOR MAKING STEREOTYPE-PLATES.

SPECIFICATION forming part of Letters Patent No. 320,713, dated June 23, 1885.

Application filed February 23, 1884. (No specimens.)

To all whom it may concern:

Be it known that I, CHARLES A. SKENE, of Westmoreland, in the county of Pottawatomie and State of Kansas, have invented certain new and useful Improvements in Impression-Sheets for Making Stereotype-Plates; and I do hereby declare the following to be a full, clear, and exact description of the invention, such as will enable others skilled in the art to 10 which it pertains to make and use it.

My invention relates to an improvement in matrices for stereotype-plates; and it consists in a paper impression-sheet that is prepared by coating blotting or other soft paper with a 15 mixture that is composed of glycerine and plumbago, for the purpose to be more fully set forth hereinafter.

The object of my invention is to enable me to obtain stereotype-plates for printing purposes direct from matrices made by telegraph or type-writing machines, and thus to obviate the necessity of having to prepare type-forms in order to obtain a cast, thus saving the time, labor, and expense of composition, distribution, and making up that are now necessary prerequisites to the operation.

In order to carry my process into operation, I take a sheet of blotting or other soft paper, of suitable size and thickness, and coat it 30 evenly on both sides with a brush that is dipped into a mixture of glycerine and plumbago. To make this preparation, plumbago is finely ground in a mortar, and a sufficient quantity of glycerine mixed with it to form a thin paste. When the paper has thoroughly 35 absorbed the mixture, it is passed between heated rollers until its surfaces have become

perfectly smooth. The paper so prepared is placed in a type-writing machine of any of the common forms, and the writing proceeded with as upon ordinary paper. The types will make impressions in the paper sufficiently deep to form a mold or matrix in which a stereotype-plate can be cast in the ordinary manner for use in an ordinary printing-press.

I am thus enabled to prepare stereotype-plates for printing purposes without the necessity of having to prepare type-forms, thus effecting a saving of time, labor, and expense 50 to a degree that has been heretofore unknown. It will be obvious that a telegraph printing-machine may be thus employed in preparing the mold or matrix, and operated from a distant point, which will be found of great practical utility.

After the impression is taken upon the prepared paper it is dried as much as possible before stereotyping.

Having thus described my invention, I claim—

An impression sheet for forming a matrix or mold for stereotype-plates, that is composed of soft blotting-paper or other fibrous substance impregnated with a mixture of glycerine and plumbago, substantially as described.

In testimony whereof I affix my signature in presence of two witnesses.

CHARLES A. SKENE.
